UNITED STATES PATENT OFFICE.

CHARLES FREDERICK BAILEY, OF LAWTON, ENGLAND.

KILN FOR FIRING POTTERY AND OTHER WARE.

Application filed August 10, 1921. Serial No. 491,213.

To all whom it may concern:

Be it known that I, CHARLES FREDERICK BAILEY, subject of the King of Great Britain and Ireland, and resident of Greenbank, Lawton, in the county of Chester, England, earthenware manufacturer, have invented certain new and useful Improvements in Kilns for Firing Pottery and Other Ware, of which the following is a specification.

My invention relates to improvements in kilns for firing pottery and other ware, the object being means to enable a great quantity of ware to be expeditiously and economically treated, and means for consuming the products of combustion so as to prevent the issue of black smoke through the chimney of the kiln.

My invention consists essentially in the use of three kilns arranged in close proximity to one another, two of the kilns being arranged below and separated by an opening or arched passage where the fires are located, with a third kiln constructed above the said arched passage; all the three kilns being heated by the circulation of heat from the fires in the opening or arched passage; means for expeditiously cooling down the ware after the firing thereof; means for excluding the cold air to the fire-places, flues and brick-work in order to retain the heat after the firing of the ware is completed thereby lessening the amount of fuel required for the next firing; and means for consuming the products of combustion so as to prevent the issue of black smoke from the chimney of the kiln.

My invention will be fully described with reference to the accompanying drawings, in which

Fig. 1 is a sectional elevation of my improved kiln, and

Fig. 2 is a sectional elevation illustrating a portion of the kiln to be hereinafter described.

According to my said invention I employ three kilns, X, Y and Z, the two lower ones X and Y being on the same level and separated by an opening or arched passage W where the fire-places a are situated, the third kiln Z being arranged above the arched passage W and communicating with the kiln chimney V. The fire-places a are arranged at each side of the opening or arched passage W so that the flame or heat from each fire passes along flues b under each of the

lower kilns X and Y up through the flues b² arranged in the walls thereof and extending over the top and down the inner side of each kiln X and Y, the heat then passing through a passage b³ and along a flue c extending over the top of the arched passage W where meeting a midfeather c² it is divided, the heat then passing through flues d arranged along the floor of the upper kiln Z up the sides and to the top thereof where it passes into a cone or conduit j and into the kiln chimney V. By this means the whole of the heat is thoroughly circulated to the three kilns X, Y and Z and utilised to the best advantage. Each of the kilns X, Y and Z is provided with an opening e. The said openings e in the lower kilns communicate with small chimneys f (shown dotted) or with heat conduits f² into the main chimney V, each of the said openings e being provided with a similar damper g hinged at its lower side g² and operated by partly rotating a rod h (Fig. 1) to move it to close either of the lower kilns X or Y, or the upper kiln Z, the particular opening e at the back of the kiln Z being also controlled by a damper g. The opening e in the back wall of kiln Z has a passage communicating with the main chimney V outside the cone or conduit j. The rod h pertaining to the kiln Z is not shown in Fig. 1, as it and the damper g are similar to those illustrated in connection with the kiln Y.

If desired the dampers g for the two lower kilns X and Y may rest in a socket g³ and be operated by a rod g⁴ extending through a hole g⁵ in the wall of the conduit f² as shown at Fig. 2. The dampers g could be operated by a chain (not shown) or other convenient means.

The small chimneys f may be arranged vertically as shown to allow the heat to pass out into the atmosphere when necessary. Instead of employing small chimneys f a conduit f² may communicate with each side kiln X and Y and with the chimney V.

In order to retain sufficient heat in the kiln walls to assist the next firing, I employ a conduit j from the upper kiln Z to the main chimney V. This conduit j may be of cone formation or of other suitable shape extending vertically inside the chimney, a hinged damper k being employed at its upper end which is opened or closed by a chain m passing over a guide pulley n so as to be operated from outside the kiln.

Air is admitted underneath the fire bars *o* along the hearth *p* and flue or conduit *q* which is in close proximity to the flame or heat flue *b*² of the lower kilns *X* and *Y*. The 5 said air flue *q* extends over the top of the kilns *X* and *Y* and then communicates with the flame or heat flue *c*, the hot air then mixing with the flame and destroying the products of combustion prior to the flame 10 or heat passing through the flues *d* of the upper kiln *Z*. The passage of the cold air to the flues *q* is regulated by dampers *r* which are hinged at their lower ends *r*² and moved by suitable rods. The dampers *r* are shown 15 closed on the drawing, they are moved to the vertical position to allow for the passage of air through the flues *q*. The air through the flues *q* is greatly heated during its passage round the lower kilns prior to meeting 20 the flame, the flue *q* being increased in size as shown to form a hot air chamber over the top of the kilns *X* and *Y* where the heat is greatest this being for the purpose of slightly delaying the air and considerably 25 increasing its temperature to effectively treat or destroy the products of combustion which it may come in contact with during its travel to the uppermost kiln *Z*.

In order to greatly increase the intensity 30 of heat to the upper kiln *Z* when necessary a passage or by-pass *s* is employed above the fire mouths or fire-places *a* with a controlling damper *s*² which when opened allows a direct upward travel of flame there- 35 through into the passage *b*³ and up the flues *c* to the flues *d* in the walls of the uppermost kiln *Z*. Normally the passage or by-pass *s* is kept closed but it may be opened to expedite the firing in the top 40 kiln *Z* when the two lower kilns *X* and *Y* are working at the required heat tempera- ture.

During the firing of the ware in each of 45 the three kilns *X*, *Y* and *Z* the dampers *g* are kept closed but after the firing has been completed and it is desired to "cool down" the dampers *g* are opened to allow the egress of the heat from the interior of each kiln *X*, *Y* and *Z*, the heat from each 50 of the lower kilns then passing through the small chimney *f* to atmosphere, or through the heat conduit *f*² to the main chimney *V* as before referred to, the heat passing through opening *e* in the upper kiln *Z* is 55 conducted through a passage in the brick-work to the main chimney *V*.

It will be understood that the interior 60 of the three kilns *X*, *Y* and *Z* can be cooled down by operating the dampers *g* to allow for exit of heat through the openings *e* which communicate with the main chimney *V*, without interfering in any way with the heat conduits or flues *b*, *c* and *d*. All the 65 flame or heat from the said flues *b*, *c* and *d* is collected in the cone or conduit *j* which

can be closed by the damper *k* so that the heat is retained therein whilst the interior of all the three kilns *X*, *Y* and *Z* are cooling down, the stored up heat in the cone *j* and the brickwork being of great value 70 for the next firing of the kiln.

Instead of the small chimneys *f* being arranged to convey the heat to atmosphere, such waste heat may if desired be conveyed to a stove or chamber and utilised to dry 75 the ware as will be understood.

I prefer to retain the heat in the kiln walls or flues to expedite the next firing, by regulating or closing the damper *k* to prevent the egress of heat through the chimney *V* as this does not interfere with the passage through the archway *W* which enables easy access to and from the kiln and all the kiln fires. If desired the opening 80 or arched passage *W* between the two lower kilns *X* and *Y* may be closed by a door or doors. Assuming the arched passage *W* between the two lower kilns is built up at one end, a door (not shown) may be situated at the other end to completely close 85 up the passage but where the opening or passage *W* is arranged to extend right through between the two lower kilns, two doors could be provided, one at each end 90 of the passage, for the purpose stated, in which case either of the two doors could be opened during the firing and closed when the "cooling down" of the ware is taking place. Such doors may be arranged to slide in guideways or be mounted on hinges or 95 carried in any other suitable way.

To expedite the "cooling down" of the ware in all the three kilns after firing is accomplished I arrange for the displacement of the fire grates to dislodge the burning fuel. For this purpose the fire bars *o* are carried on an inclined slidable frame *t* which rests on fixed bearers *u*. The said slidable frame *t* extends longitudinally of each fire-place *a* and has two or more racks *t*² to engage pinions *t*³ secured to rotatable shafts *t*⁴ rotatable in bearings (not shown) fixed on the kiln. By the rotation of the shaft *t*⁴, the pinions *t*³ slide the frame *t* carrying the fire bars *o* the fuel thereon falling into the ash-hole 2, water therein extinguishing the fires. When the fires are extinguished, the damper *k*, on the top of the cone or conduit *j*, is closed so as to retain the maximum amount of heat for the 100 next firing.

To retain the heat round the top kiln *Z* which is farthest away from the fires I may employ an extra thickness of brickwork for the walls 3 of the uppermost kiln *Z*.

What I claim as my invention and desire to secure by Letters Patent is:—

1. In a pottery kiln, an arched passage, a kiln arranged at each side of the passage, each kiln being provided with a fire-place 130

arranged crosswise of it and adapted to be fired from within the said passage, and a third kiln arranged above the said passage and provided with a chimney, all three kilns 5 being provided with heating flues extending around them and connecting the two fire-places with the said chimney.

2. In combination with a kiln as set forth in claim 1, a conduit arranged in the 10 chimney above the third kiln and provided with a damper at its upper part so that heat may be retained in the conduit to assist the next firing.

3. In combination with a kiln as set forth 15 in claim 1, passages for hot air extending around the two lower kilns and connecting the lower parts of their fire-places with

the heating flues at points where they approach the under part of the third kiln so that the products of combustion may be 20 consumed before they pass around the third kiln.

4. In combination with a kiln as set forth in claim 1, a by-pass passage between each fire-place and the heating flues of the third 25 kiln, and a damper controlling each said by-pass passage.

In testimony whereof I have hereunto set my hand in the presence of two witnesses.

30

CHARLES FREDERICK BAILEY.
